(57) CLAIM

The ornamental design for a substrate with musky camouflage pattern, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top plan view of a substrate with musky camouflage pattern. The broken line portions form no part of the claimed design.
